UNITED STATES PATENT OFFICE.

FREDRICK H. SCHUMACHER, OF JERSEY CITY, NEW JERSEY.

FAN ATTACHMENT FOR SEWING-MACHINES.

1,280,561.

Specification of Letters Patent.

Patented Oct. 1, 1918.

Application filed June 19, 1917. Serial No. 175,670.

To all whom it may concern:

Be it known that I, FREDRICK H. SCHUMACHER, a citizen of the United States, residing at Jersey City, in the county of Hudson and State of New Jersey, have invented certain useful Improvements in Fan Attachments for Sewing-Machines, of which the following is a specification; reference being had therein to the accompanying drawing.

This invention relates broadly to a sewing machine and more particularly has reference to a fan attachment especially adapted for use on sewing machines.

It is the principal aim and object of this invention to provide a device of the above character designed to be readily and quickly attached to the balance wheel of a sewing machine for directing currents of air on the operator of the machine during actuation thereof.

As an equally important object this invention embraces the provision of a fan attachment wherein the fan blades are constructed so as to assure of the directing of currents of air inwardly toward the operator of the machine.

More particularly this invention includes the provision of a fan attachment wherein the fan blades are movably attached to the attaching plate and are extended during operation of the balance wheel but are adapted to be placed in a compact collapsed form when the balance wheel is still to consequently permit of the closing of the machine.

Among the other aims and objects of this invention may be recited the provision of a device of the character described with a view to compactness, and in which the number of parts are few, the construction simple, the cost of production low and the efficiency high.

Other improvements and novel details in the construction and arrangement of the various parts of the apparatus will be brought out more in detail in the description to follow, which for a clear understanding of the invention should be considered in connection with the accompanying drawings forming a part hereof and wherein is disclosed for the purpose of illustration a convenient and satisfactory embodiment of the invention. It is to be noted in this connection that minor changes in the construction and arrangement of parts may be made without

departing from the principle of operation of the various parts.

The invention is clearly illustrated in the accompanying drawings, in which:—

Figure 1 is a front elevation showing the device attached to the balance wheel of the sewing machine;

Fig. 2 is a side elevation thereof;

Fig. 3 is a perspective detail of the invention;

Fig. 4 is a fragmentary perspective detail of the attaching plate.

Similar characters of reference are employed in all of the above described views, to indicate corresponding parts.

Referring now, more particularly, to the accompanying drawings there is illustrated a balance wheel 1 of a sewing machine while attached to the outer face thereof is an annular open attaching plate 2 the free edges of which are cut in divergent relation with each other as indicated at 3 to facilitate application, and the plate is also provided with openings 4 through which pass fastening devices 5 designed for securing the plate in a substantially rigid position on the wheel. A plurality of lugs 6 are struck out from the plate adjacent the inner edge thereof and at uniformly spaced intervals.

These lugs constitute stops and are preferably projected at substantially right angles from the outer face of the plate as indicated in the drawings. A plurality of pins indicated generally by the numeral 7 are now employed and each preferably consists of a shank 8 having a head 9 on the outer end thereof while the inner end is reduced and threaded exteriorly as at 10 for removable engagement with the correspondingly formed openings 11 in the plate 2 and adjacent each of the lugs 6 there being preferably three in number which are desirably arranged at uniformly spaced intervals with respect to each other.

With a view toward providing the improved means for directing currents of air directly on the operator of the machine, blades indicated in their entireties by the numeral 12 are employed. There are desirably three of these blades and on the inner end of each is formed a sleeve 13 being preferably continued from the blade to assume its sleeve-like form. Each sleeve is slit longitudinally and transversely while the portion lying therebetween is bent outwardly.

100
105
110

to provide a lug 14 preferably arranged in the plane at substantially right angles to the longitudinal axis of the adjacent pin shank 8 and about which the adjacent sleeve is 5 partially rotatably arranged. The inner edge of the fragmentary portion of the sleeve as indicated by the numeral 15 and the inner edge of the adjacent lug 14 which is in alignment therewith provide a bearing which is 10 arranged in close relation with the outer surface of the plate to limit movement of the sleeve in one direction while the opposite edge of the sleeves coöperates with the adjacent head to limit the lateral movement of 15 the fan blade. With respect to each fan blade 12 it will be observed that the inner portion of the body thereof is arranged in a plane at substantially right angles to the plane of the attaching plate 2 while the intermediate portion is twisted as at 16 so 20 that the outer portion will be arranged substantially at right angles to the plane of the inner portion but slightly pitched and serves to force currents of air directly inwardly 25 upon the operator of the machine during rotation of the wheel. In this connection it will be also observed that the lugs 14 coöperate with the adjacent lugs 6 in limiting outward movement of the blades during 30 rotation of the balance wheel, the blades being adapted to swing outwardly owing to centrifugal action. However, when the wheel is still, the blades may be partially swung about their pivots so as to be suspended 35 from the plate and be arranged in a compact, collapsed form to permit of the application of a cover or the like on the sewing machine, not shown.

It is believed in view of the foregoing description that a further detailed description of the operation of the invention is entirely unnecessary. Likewise it is thought that the advantages of the invention will be readily apparent.

As many changes could be made in the above construction and many apparently widely different embodiments of this invention could be made without departing from the scope thereof, it is intended that all matter contained in the above description or

shown in the accompanying drawings shall be interpreted as illustrative and not in a limited sense. It is also to be understood that the language used in the following claims is intended to cover all the generic and specific features of the invention herein described and all statements of the scope of the invention which as a matter of language might be said to fall therebetween.

Having thus fully described this invention, what is claimed as new and desired to be secured by Letters Patent is—

1. An attachment of the character described, including an attaching plate, a plurality of fan blades mounted thereon, each blade consisting of a body the inner portion of which is arranged at substantially right angles to the plane of the plate, the intermediate portion of the body of each blade being twisted and the outer portion of each blade being arranged in a plane at substantially right angles to the plane of the inner portion but slightly pitched substantially as described.

2. An attachment of the character described, including an annular open attaching plate adapted for engagement with the outer face of the balance wheel of a sewing machine, means for securing the plate, a plurality of stops struck out from the plate adjacent the inner edge thereof and arranged at uniform intervals with each other, a plurality of fan blades, a sleeve formed on the inner end of each fan blade, a plurality of headed pins having their shanks loosely engaged in the sleeves on the blades to pivotally mount the blades and having their extreme inner ends removably anchored in the plates adjacent the stops and projecting outwardly from the outer face of the plate, and a plurality of lugs formed on the inner edges of the sleeves for coöoperating with the stops on the blades for limiting the movement of the blades during rotation of the wheel and permitting of the collapsing of the blades into a compact form when the wheel is idle.

In testimony whereof I affix my signature.

FREDRICK H. SCHUMACHER.
